(57) **CLAIM**

The ornamental design for a toothbrush, as shown and described.

DESCRIPTION

FIG. 1 is a perspective view illustrating a first preferred embodiment of the claimed toothbrush;

FIG. 2 is a front elevational view of a first preferred embodiment of the claimed toothbrush;

FIG. 3 is an elevational view of a first side of a first preferred embodiment of the claimed toothbrush;

FIG. 4 is an elevational view of the rear of a first preferred embodiment of the claimed toothbrush;

FIG. 5 is an elevational view of a second side, opposite from the first side shown in FIG. 3, of a first preferred embodiment of the claimed toothbrush;

FIG. 6 is a top planar view of a first preferred embodiment of the claimed toothbrush;

FIG. 7 is a bottom view of the underside of a first preferred embodiment of the claimed toothbrush;

FIG. 8 is a perspective view illustrating a second preferred embodiment of the claimed toothbrush;

FIG. 9 is a front elevational view of a second preferred embodiment of the claimed toothbrush;

FIG. 10 is an elevational view of a first side of a second preferred embodiment of the claimed toothbrush;

FIG. 11 is an elevational view of the rear of a second preferred embodiment of the claimed toothbrush;

FIG. 12 is an elevational view of a second side, opposite from the first side shown in FIG. 10, of a second preferred embodiment of the claimed toothbrush;

FIG. 13 is a top planar view of a second preferred embodiment of the claimed toothbrush; and,

FIG. 14 is a bottom view of a second preferred embodiment of the underside of the claimed toothbrush.

The parts shown in broken lines in FIGS. 1-14 are shown for illustrative purposes only and form no part of the claimed design.

1 Claim, 8 Drawing Sheets
